[57] CLAIM

The ornamental design for a faucet handle, as shown and described.

DESCRIPTION

FIG. 1 is a top perspective view of a faucet handle showing my new design;
FIG. 2 is a side elevational view thereof, the other sides being the same as the side shown;
FIG. 3 is a top plan view thereof;
FIG. 4 is a top perspective view of a modified form of the faucet handle shown in FIG. 1;
FIG. 5 is a side elevational view of FIG. 4, the other sides being the same as the side shown; and
FIG. 6 is a top plan view of FIG. 4.

FIG . 1.

FIG . 2.

FIG . 3.

FIG .4.

FIG .5.

FIG .6.
